J. K. NELSON. OF GREEN POINT, NEW YORK.

Letters Patent No. 83,991, dated November 10, 1868.

IMPROVEMENT IN DIVIDED CAR-AXLE.

The Schedule referred to in these Letters Patent and making part of the same.

To all whom it may concern:

Be it known that I, J. K. NELSON, of Green Point, in the county of Kings, and State of New York, have invented a new and useful Improvement in Divided Car-Axes; and I do hereby declare that the following is a full, clear, and exact description of the same, reference being had to the accompanying drawings, forming a part of this specification, in which—

Figure 1 represents a longitudinal view of a divided car-axe constructed according to my invention;

Figure 2 represents a longitudinal section thereof; and

Figure 3, a transverse section of the same, taken through the line *xx*.

Similar letters of reference indicate corresponding parts in the several figures.

This invention consists in the novel construction of a divided car-axe with revolving central boxing, having an oil-receptacle attached to and communicating therewith, and with removable collars or tie-rings arranged therein for preventing separation of the joint, whereby a uniform lubrication of the journal by the renewed application of the lubricant at every revolution of the boxing is effected, and whereby provision is made for the removal of worn collars, and the substitution of new ones, without incurring the expense of supplying entirely new boxing.

In order that others may understand the construction and operation of my invention, I will proceed to describe it with reference to the drawings.

A is a car-axe, carrying upon its extremities a pair of car-wheels, *B B*, of the ordinary construction, and rigidly attached to the axe in the usual way. Said axe *A* is composed of two parts, or is divided transversely at its centre, and the inner ends thereof, which may be designated as *a a'*, are supported within a box, *C*. Said box *C* is of sufficient length and strength for the proper support of the said inner extremities *a a'* of the divided axe *A*, and is made to clasp firmly, or is otherwise rigidly attached to one of the said inner extremities, as *a*, so as to revolve by means of the rotation of the same, while the opposite portion or section, *a'*, of the said axe is permitted to turn loosely therein, so as thereby to provide for the variation in the velocities of the inner and outer wheels while running over curves in the road. Upon the portion of the said box

C which contains the loose portion or section *a'* of the axe, is arranged a receptacle, *D*, for containing oil or other lubricating-substance or material. Said receptacle *D* is provided with openings *d d'*, the one for the pouring in of the oil or lubricant, and the other for the insertion and removal of suitable absorbent material, designed for absorbing and retaining the said lubricant when necessary for preventing the too free lubrication of the joint. It is also provided with communicating-openings, *c*, which conduct the lubricating-material into the box, at every revolution of the same. Arranged within the said box *C* is any desirable number of removable collars or tie-rings, *e*. Said collars or rings *e* are fitted within annular spaces or grooves formed around the axe, partly within the axe and partly within the box, for the purpose of retaining the axe within the box, and are constructed of two parts, for the more ready application thereof to said spaces or grooves around the axe. These collars or rings *e*, sustaining the full force of all diverging or outward tendency of the wheels, soon become worn, whereupon they may be removed upon the opening of the box, and their places refilled by new ones, thereby avoiding the expense of new boxing, an expense which cannot be avoided by the use of the ordinary divided axe, having said collars attached as a fixture thereto, or to the boxing thereof.

f is a collar, composed of leather, or other flexible or yielding material. Said collar *f* is fitted within a groove, cut within the box *C*, at a point near the extremity of that portion thereof which contains the loose section *a'* of the axe, so as to fit closely around the said axe, and is designed for retaining the oil within the box, and prevent the unnecessary waste of the same.

What I claim as my invention, and desire to have secured by Letters Patent, is—

The divided car-axe *A*, constructed as described, with the revolving self-lubricating box *C*, removable collars *e*, and flexible collar *f*, substantially as and for the purpose herein set forth.

J. K. NELSON.
